United States Patent Office

Des. 216,400

Patented Dec. 30, 1969

216,400

PET BED

Suzanne Schwertley, 610 W. 110 St.,
New York, N.Y. 10025

Filed Sept. 26, 1967, Ser. No. 8,740

Term of patent 14 years

Int. Cl. D30—99

U.S. Cl. D30—41

FIG. 2

I claim:

The ornamental design for a pet bed, as shown.
